Fig. 4

Fig. 5.

Fig. 6.

Fig. 8.

Fig. 7.

Fig. 9.

Fig. 10.

Fig. 11.

Fig. 12.

FIG. 1 is a front perspective view of a telephone wall cabinet showing the design;

FIG. 2 is a side elevational view thereof;

FIG. 3 is a top plan view thereof;

FIG. 4 is a bottom plan view thereof;

FIG. 5 is a front perspective view of a modified form of the telephone wall cabinet;

FIG. 6 is a side elevational view of the form shown in FIG. 5;

FIG. 7 is a top plan view of the form shown in FIG. 5;

FIG. 8 is a bottom plan view of the form shown in FIG. 5;

FIG. 9 is a front perspective view of still another modified form of the telephone wall cabinet;

FIG. 10 is a side elevational view of the form shown in FIG. 9;

FIG. 11 is a top plan view of the form shown in FIG. 9;

FIG. 12 is a bottom plan view of the form shown in FIG. 9.

The sides not shown in the drawing herewith are substantially the same in appearance as the sides shown in FIGS. 2, 6, 10, respectively.

The dot-dash lines of FIGURES 2, 6 and 10 are for illustrative purposes only.

What is claimed is:

The ornamental design for a telephone wall cabinet, as shown and described.
